CLAIM

I claim, the ornamental design for a light emitting diode package, as shown and described.

DESCRIPTION

FIG. 1 is a front perspective view of the light emitting diode package, showing my new design;

FIG. 2 is a front elevational view of the light emitting diode package of FIG. 1;

FIG. 3 is a rear elevational view of the light emitting diode package of FIG. 1;

FIG. 4 is a left side elevational view of the light emitting diode package of FIG. 1;

FIG. 5 is a right side elevational view of the light emitting diode package of FIG. 1;

FIG. 6 is a top plan view of the light emitting diode package of FIG. 1;

FIG. 7 is a bottom plan view of the light emitting diode package of FIG. 1;

FIG. 8 is a front perspective view of the light emitting diode package, in which an LED and a Zener diode are shown in broken lines and form no part of the claimed design; and,
FIG. 9 is a cross-sectional view of the light emitting diode package taken along 9—9 in FIG. 8.
